THERMOSTAT HOUSING

Andrew O. Hensel, Milwaukee, Wis., assignor to
Perfex Corporation, Milwaukee, Wis., a corpo-
ration of Wisconsin

Application June 2, 1949, Serial No. 2,999

Term of patent 14 years

(Cl. D52—7)

To all whom it may concern:

Be it known that I, Andrew O. Hensel, a citizen of the United States and a resident of Milwaukee, in the county of Milwaukee and State of Wisconsin, have invented a new, original, and ornamental Design for a Thermostat Housing, of which the following is a specification, reference being had to the accompanying drawing, forming a part thereof.

Fig. 1 is a perspective view of a thermostat housing, showing my new design;

Fig. 2 is a front elevational view thereof;

Fig. 3 is a side elevational view thereof; and

Fig. 4 is a top view.

I claim:

The ornamental design for a thermostat housing, substantially as shown.

ANDREW O. HENSEL.
